THIN SHEET BLANKING MECHANISM

Isaac L. Wilcox, Fulton, N. Y., assignor to Oswego Falls Corporation, Fulton, N. Y., a corporation of New York

Application October 12, 1936, Serial No. 105,177

9 Claims. (Cl. 164—29)

This invention relates to cutting mechanism for forming blanks of thin sheet material. More particularly, the invention is a cutting mechanism particularly adapted to operate upon sheet material which is exceptionally thin, and which has the characteristic of possessing exceptionally high tensile strength until the sheet has been punctured, or ruptured, and which sheet possesses the further characteristic of being particularly resistant to being cut or sheared. These characteristics of the material make it exceedingly difficult to cut or blank with the conventional punch and die structure. Certain cellulose materials possess this characteristic. For example, Cellophane.

Insofar as I am aware, the only practical method employed at the present time for forming blanks of such material is to employ a rotating knife. That is, the material is first cut into sheets of approximately the size of the blank, and several of these sheets are arranged in stack formation and while so positioned, a rotating knife is moved into engagement with the stack, and the blanks are cut by the circular motion of the knife. While this method is practical, insofar as the severance of the blanks from the material is concerned, it is impractical in that the severed blanks of this exceedingly thin and slippery material must be subsequently handled individually during the conversion of the blank into the article for which the blank is intended.

The general object of my invention is a cutting mechanism of particularly economical construction and which, because of its novel structure, will efficiently sever individual blanks from the sheet material, and which operates to sever a large volume of blanks without the necessity of resharpening or replacing the cutting blade.

Another object of the invention is a cutting mechanism for forming blanks of such material, which mechanism is so constructed that it is adapted for use on the blank converting machine, such as shown in my copending application, Sr. No. 105,411 filed October 13, 1936, thereby avoiding the necessity of manually, or otherwise, handling the blank after it has been severed from the sheet.

The invention consists in the novel features and in the combinations and constructions hereinafter described and claimed.

In describing this invention, reference is had to the accompanying drawing in which like characters designate corresponding parts in all the views.

Figure 1 is a partial plan view of the cutting mechanism.

Figure 2 is a cross sectional view.

Figure 3 is a fragmentary, enlarged cross sectional view.

Figure 4 is a fragmentary elevational view of the cutting blade.

The invention comprises generally, a die member of annular formation adapted to support the sheet, and being provided with an aperture complementary to the contour of the blank, a cutter support, said die and support being arranged to have relative axial movement, a blade detachably secured to said support and extending therefrom toward the die, the extending edge of the blade being provided with a plurality of teeth arranged, upon contact of the blade with the sheet, to penetrate the sheet at a plurality of points, and to subsequently sever the sheet intermediate the penetrations.

The mechanism here shown is used to sever a blank in the form of a disk from sheet material, and comprises a die member 10 and a cutter support 11. The die and support are arranged to have relative axial movement. As here shown, the die support 10 is intended to be mounted upon a stationary part of the machine, and is provided with diametrically opposed bosses 12, in which bushings 13 are inserted. The support 11 is provided with similar bosses 14 in which are secured guide pins 15 which are slidably mounted in the bushings 13 and which are connected at their lower end to connecting rods 16 associated with the movable mechanism of the machine. Insofar as this invention is concerned, any conventional mechanism may be employed to effect relative axial movement between the die 10 and the support 11, or to move the support 11 axially of the die 10.

The die is provided with a centrally arranged aperture 17, and the support 11 with a similar aperture 18. The under side of the support 11 is formed with a counterbore arranged concentrically of the aperture 18, and in which is mounted a circular cutter blade 20 which is preferably formed of thin, flexible steel. The blade 20 may be of annular formation, or it may consist of a flat blade bent into circular form. The blade 20 is detachably secured in the counterbore of the support 11 by an expandable ring 21, here shown as being split at one side as at 22, and being expanded by a tapered pin 23. The ring 21 is expanded to press the blade 20 radially outwardly against the counterbore in the support 11, and the blade is thus rigidly but detachably secured.

to the support, and extends downwardly from the support toward the surface of the die 10.

A presser member 24, in the nature of a ring, encircles the blade 20 and is carried by one or more studs 25 slidably mounted in the support 11. The presser ring 24 is urged outwardly by helical compression springs 26 encircling the studs 25, and the arrangement is such that normally, or when the die 10, support 11, are in spaced apart relationship, the presser ring 24 encircles the lower edge of the blade 20 and extends downwardly a short distance therefrom.

The presser ring 24 may be formed with an annular rib 27 on its under side adjacent the bore of the ring, as shown in Figure 3, and the face of the die toward the upper side of a wear ring 28 formed with a complementary annular recess 29. As the support 11 is moved toward the die 10, the rib 27 contacts the sheet 30 pressing the same into the recess 29. This action tends to draw the sheet taut, and it is held in this condition by being clamped between the presser ring 24 and the wear ring 28 of the die. Upon further downward movement of the blade carrier 11, the blank is severed from the sheet.

The lower or extending edge of the blade 20 is formed with a plurality of teeth 32. The teeth 32 resemble generally the teeth of a saw, and are formed or arranged with the points 33 of the teeth extending in the same direction. That is, the forward side 34 of the teeth extend in an angular relationship to the axis of the blade, and the rear side 35 extends at an appreciably greater angle, whereby the points 33 of the teeth are arranged to one side of the perpendicular drawn from the base of the teeth.

The hardened wear ring 28 is of such dimensions as to receive the toothed edge of the blade 20 upon movement of the support towards the die. The presser ring 24 engages the sheet and clamps the marginal portion of the same against the ring 28, as above described. Upon further movement of the support, the ends 33 of the teeth puncture or penetrate the sheet, and upon further movement of the support and blade 20, the knife edges 35 of the teeth sever the sheet intermediate the penetrations. Due to the fact that the points 33 of the teeth extend forwardly of the base of the teeth, the sheet is completely severed between the penetrations.

Due to the fact that the blade initially only penetrates the sheet with the sharp points 33 of the teeth, very little pressure is established between the support and the die, with the result that the cutting mechanism may be of comparatively light construction and require little power for operation. With these advantages, the cutting mechanism is adapted to be incorporated in the blank converting machine. Attention is particularly called to the fact that with this mechanism, both the die and the support 11 may be of annular formation permitting the entire interior of the die and support to be open for subsequent operation of mechanism employed in converting the blank into the desired article.

What I claim is:

1. Cutting mechanism for forming blanks of thin sheet material comprising a die member adapted to support the sheet and being provided with a centrally arranged aperture to receive the severed blank, a cutter support, said die and said support being arranged to have relative axial movement, a cutter carried by said support and extending therefrom towards said die member, a presser member encircling said cutter

and being slidably mounted on said support and being operable upon movement of said support toward the die to press the marginal portion of the sheet against the face of the die, said cutter blade being formed on its extending edge with a plurality of teeth arranged to penetrate the sheet at a plurality of points upon contact of the blade with the sheet, and to subsequently sever the sheet intermediate said penetrations. 5

2. Cutting mechanism for forming blanks of thin sheet material comprising a die member adapted to support the sheet and being provided with a centrally arranged aperture, a support member movable axially toward and from said die member, a presser member arranged intermediate said die member and said support and being slidably mounted on said support and being operable upon movement of said support toward the die to press the marginal portion of the sheet against the face of the die, a cutter 10 blade carried by said support and extending toward said die, said extending portion being encircled by said presser member and the edge of the blade being formed with a plurality of teeth arranged to penetrate the sheet at a plurality of 15 points upon contact of the blade with the sheet and upon further movement of the blade toward the die to sever the sheet intermediate said penetrations. 20

3. Cutting mechanism for forming blanks of thin sheet material comprising a die member adapted to support the sheet and being provided with a centrally arranged aperture, a cutter support, said die and support being arranged to have relative axial movement, a cutter carried by said support and extending therefrom toward said die member and being formed with a plurality of teeth arranged, upon contact of the cutter with the sheet, to penetrate said sheet at a plurality of points, and to subsequently sever the sheet intermediate said penetrations, and means carried by said support and cooperable with the die member to draw the sheet radially and maintain the same in taut condition during the penetration and severance of the sheet. 30

4. Cutting mechanism for forming blanks of thin sheet material comprising a stationary member of annular formation adapted to support the sheet during the cutting operation, a movable member of annular formation, a cutter blade 35 detachably secured to the movable member and extending therefrom toward said stationary member, the extending edge of said blade being formed with saw-like teeth, with the cutting point of each tooth overlapping the base of 40 the adjacent tooth. 45

5. Cutting mechanism for forming blanks of thin sheet material comprising a die member of annular formation adapted to support the blank during the cutting operation, a cutter carrier of 50 annular formation arranged concentrically with said die member and being movable toward and from the same, said carrier member being formed with a counterbore, a cutter blade of thin, flexible material detachably secured in said counterbore and extending toward said die, said extending portion of the cutter blade being provided with a plurality of saw-like teeth, with the point of each tooth arranged to overlap the base of the adjacent tooth. 55

6. A cutting mechanism for forming blanks of thin sheet material comprising an annular die member, an annular cutter member provided with saw-like teeth extending toward said die member, said members having relative axial 60 movement, 70

movement, the teeth of the cutter member being formed with the front and rear side edges thereof extending in the same direction, and with the rear edge of each tooth overlapping the point of the adjacent tooth, whereby upon relative axial movement of said members, the points of the teeth penetrate the sheet and subsequently the rear edges of the teeth sever the sheet intermediate said penetrations.
